UNITED STATES PATENT OFFICE.

PHILIP S. SMITH, OF PHILADELPHIA, PENNSYLVANIA.

BLANK-GUMMING MACHINE.

No. 890,309.

Specification of Letters Patent.

Patented June 9, 1908.

Application filed July 19, 1904. Serial No. 217,182.

To all whom it may concern:

Be it known that I, PHILIP S. SMITH, a citizen of the United States, residing at Philadelphia, in the county of Philadelphia and 5 State of Pennsylvania, have invented new and useful Improvements in Blank-Gumming Machines, of which the following is a specification.

My invention has relation to new and useful 10 improvements in blank gumming machines employed in the manufacture of paper boxes, and it is especially designed to apply an adhesive to a paper blank which is afterwards to be applied as a covering for a previously 15 completed box shell in such a manner as to produce a box of the type generally designated as "loose wrapped", that is, a box having a covering blank wrapped smoothly around the exterior walls thereof, 20 with its marginal edges folded over the upper edges of the walls of the box shell, turned down into the box and pasted to the inner faces of said walls, the covering being unattached to the exterior of the box.

25 In an application filed July 29, 1903, and bearing Serial Number 167,440, I have shown and described a gumming and covering machine constructed to apply an adhesive to the marginal edges of a covering blank, and associated with the adhesive applying devices, is an automatic stripper to remove the gummed blank from the said devices, and also a mechanism for transferring the blank from the stripper to means for applying the blank to a 30 box shell, and it will be seen, upon reference to said application, that all of the steps mentioned are automatically performed in sequence until the box is completed. In the present invention, however, the purpose is to

40 provide a gumming machine independent of any determined covering mechanism, in which the blanks, after having the adhesive applied, may be removed and transferred to the covering machine by hand, thereby dispensing with a transfer means and rendering the gumming machine capable of use in connection with any covering machine desired.

45 The primary object of the invention is to provide a gumming machine in which the blank will not be permitted to adhere to the devices for applying the adhesive, and which embody means operating to hold the blank during the operation of gumming and to re-

lease the blank to permit it to be withdrawn after the adhesive has been applied.

55

A further object is to provide in connection with devices to apply gum to the margins of the blank, means to engage the major portion of the blank with the exception of the portion to which the adhesive is directly applied, to hold the blank flat and stationary during the gumming operation, and to hold the blank during the return of the gum applying devices so that the blank will be stripped from said devices, and subsequently released by said means to permit its withdrawal.

60

65

A further object is to provide a combined stripper and means for holding the blank, which will be controlled by the gum applying means, to both engage and release the blank.

70

A further object is to provide means for suspending operation of the gum applying devices, when the machine is started to insure an effectual and complete application of adhesive to the said devices, so that the defective gumming of the blanks may be avoided when the machine is started.

75

Broadly and generally stated, the invention embodies a support for one or a number of covering blanks, a gum applying device movable toward and away from the blank and constructed to apply an adhesive to the marginal edges of the blank, and means for holding the blank flat prior to, and during the application of the adhesive and operating to release the blank after the adhesive has been applied.

80

85

I have fully and clearly illustrated my invention in the accompanying drawings to be taken as a part of this application and wherein—

90

Figure 1, is a view in front elevation of a gum applying machine embodying my invention, both the gum applying means and the stripper being elevated out of engagement with the uppermost of a pack of blanks, the said means being in position to receive a supply of adhesive; Fig. 2, is a view in end elevation, part of the frame-work being in section, the elements bearing the same relation as shown in Fig. 1, and also illustrating the means for operating the said elements. Fig. 3, is a view in front elevation, showing the stripper in engagement with the top blank of the pack, and the adhesive applying devices bearing relation thereto as immediately sub-

100

105

sequent to stamping the blank and on its return or up stroke. Fig. 4, is an enlarged detail view of the means for holding the adhesive applying means against operation to 5 permit a complete and effectual supply of adhesive to be applied thereto at the time the operation of the machine is commenced.

Referring to the drawings, the reference numeral 1, designates a supporting table, 10 disposed in a horizontal plane and of such area as to suit it to the purposes to which it may be put, said table being supported upon suitable legs or standards 2, the construction of which is immaterial to the purposes of this 15 invention. Extending through this table 1, and vertically movable up and down therethrough, is a feed post 3, carrying at its upper end a rectangular supporting plate 4, adapted to receive flatwise a covering blank, 20 or a pack of blanks *a*, as shown in the several figures of the drawings. Adjustably supported upon the table 1, are a plurality of vertical gages 5, coöoperating with slots (not shown) in the supporting plate 4, by means 25 of which the space for the confinement of the blanks to be gummed may be regulated to suit the size of said blanks, and in order to center them in proper position beneath the gumming means, substantially as shown and 30 described in my former application bearing date and serial number heretofore referred to.

Rising above the table 4, and extending thereover, is a supporting frame upon which are arranged in operative relation the various elements embodying the means for applying the adhesive to the blanks, and also the holding and stripping means for the blanks being acted upon. This supporting frame is constructed of two oppositely ar- 35 ranged curved members 6, 6, the lower ends of which are rigidly mounted on the table 1, which extends over the table towards each other and meet at their upper terminals to constitute a supporting arch 7, the upper 40 ends of said members being spaced apart from each other and provided with vertically projecting extensions 8, 9, which are connected at their upper ends by a cross-piece 10, having a bearing aperture 11, ex- 45 tending therethrough for a purpose to presently appear. At the lower portion thereof, the meeting ends of the members 6, 6, are connected by a second cross-piece 12, having a bearing aperture 13, located in vertical 50 registration with the one in the cross-piece 10, above mentioned. Located on the opposite sides of the cross-piece 10, and adjacent each of the extensions 8, 9, respectively, are bearing brackets 14, 15, having vertical 55 openings therethrough, and upon the cross-piece 12, adjacent and on the opposite sides thereof are similar bearing brackets 16, 17, which align respectively with the brackets 14 and 15, one set of alining brackets being

upon each side of the arch 7, substantially 60 as shown in the drawings.

Extending through the bearing apertures 11 and 13, formed in the cross-pieces 10 and 12, is a vertically reciprocating plunger rod 18, said rod being of such length that during 70 its reciprocation the upper end will always extend above the cross-piece 10, and its lower end will project below the arch 7, into the space between said arch and the blank pack. Carried by the lower end of this rod 75 18, is a head 19, provided with four arms 20, upon each of which is adjustably mounted an adhesive applying device consisting of a flexible strip 21, secured to the lower end of a depending bracket 22, which latter has an 80 opening in its upper end which receives one of the arms 20, to which it is adjustably secured by means of a set screw 23. The construction of the adhesive applying head as above described, is substantially the same as 85 that disclosed in my prior application, and the arrangement is such that the adhesive applying strips may be adjusted on the arms to accommodate covering blanks of different sizes.

The head 19, as above described is constructed to be lowered so that the gumming strips may be pressed into engagement with the uppermost blank of the pack, and then moved upwards so that the blank may be 90 removed from the stack after the adhesive has been supplied thereto, and the means for accomplishing these movements of said head will now be described. Extending rearwardly from the arch frame is an arm 24, in 100 the end of which is journaled a rock-shaft 25, and on this rock-shaft is a forwardly extending crank arm 26, having a link connection 27, with a block 28, which is rigidly mounted upon the plunger rod 18. This shaft 25, is 105 also provided with an additional crank arm 29, to the free end of which is pivoted one end of a connecting rod 30, the opposite end of which is connected to a rock-arm 31, at a point intermediate its ends, said arm 31, being pivoted at one end as at 32, to the framework of the machine (not shown). The opposite or free end of the arm 31, carries an anti-friction roller 33, which travels upon the periphery of a strap-cam 34, secured upon 110 one of the side faces of a rotating disk 35, mounted upon a shaft 36, to which rotation is imparted in any desired manner. This cam is formed substantially as shown in the drawings, in order to obtain certain movements of the gumming head, to be more fully 115 set forth hereinafter.

Carried at the upper end of the plunger rod 18, is a collar 36', provided with a laterally projecting arm 37, the end of which has secured thereto one end of a connecting rod 38, the opposite end of which engages with any suitable means, not shown, for imparting to 120 125

the blank support an intermittent vertical movement toward the gumming head, so that the movement of the plunger rod will operate to move the pack of blanks upwardly 5 so that the uppermost blank be brought to a proper height to be operated on by the gumming head.

It is evident that in the operation of the machine, as above described, when the head 10 is retracted after having applied the adhesive to the blank, that the tendency will be for said blank to adhere to the flexible strips 21, and be carried upwards with the head, so that the ready removal of the blanks from 15 the gumming machine will be obstructed and the liability of tearing or marring the blanks be increased, and in order to obviate the exigencies mentioned, I provide in connection with the adhesive applying head, a means 20 for holding the blank flat and stationary during the period the adhesive is being applied thereto, and stripping the same from the head subsequent to the gumming operation when the head is retracted, and this means 25 constitutes one of the salient features of the invention, and which means will now be described.

Extending through each pair of bearing brackets 15, 17, and 14, 16, is a vertically reciprocating rod 39, as shown in the drawings, there being two of said rods parallel to each other and of a length slightly greater than the plunger rod carrying the adhesive applying head, and located on opposite sides of the 35 arch and said plunger rod. At their upper ends which at all times project above the upper end of the plunger rod 18, said rods 39, are connected by means of a cross head 40, which not only serves to rigidly unite the said 40 rods and maintain them in parallel relation, but also serves as an abutment to coöperate with the plunger rod 18, in a manner to be made apparent hereinafter. The lower ends of the rods 39, terminate beneath the head 19 45 in the space between the brackets carrying the marking strips, said rods being projected between diagonally opposite angles between the arms 20, and slidably arranged in bearing ears 41, on the head 19, as shown in the drawings. Secured to the lower ends of said rods 50 39, is a plate 42, to the underside of which, in any suitable manner, as by screws 43, is secured a holding and stripper block 44, which is of an area sufficient to cover substantially 55 all of the blank, being operated upon with the exception of that portion to which the adhesive is directly applied. It will be understood that this block 44 is readily removable and interchangeable in order that blocks 60 of different sizes may be employed commensurate to the area of the blank being acted upon and the space maintained between the adjustable strips 21.

The normal position of the stripping block 65 is that shown in Fig. 1, in which the head 19

is elevated above the blank pack and the block is raised vertically to assume a position removed from the stack within the head 19, and above the strips 21, means being provided to hold the block in the elevated position, said means being operable by the downward movement of the plunger rod 18, to release the block to permit its descent by gravity into contact with the next blank to be treated. This means for supporting the 70 stripper block in elevated position and for releasing the same in the manner stated, will now be described. Rigidly bolted as at 45, upon the outer face of the extension 9 of the frame, is the lower end 46, of a vertically extending bracket arm 47, the inner face of which, at a point adjacent the upper end of the extension 9, is provided with a bearing lug 48, in which is pivoted the lower end of a 75 vertically projecting arm 49, constituting a pivoted catch, the upper end of which terminates at a point just beneath the cross-head 40, when the stripper block is elevated and which catch engages said cross-head to maintain the said block in its upper position. 80 In order to throw the arm 49 under the cross-head 40, to engage the same, I provide the upper end of the bracket arm 47, with an inwardly directed pin 50, upon which is arranged an expansive coil spring 51, bearing 85 with its ends against the arm 49 and the bracket 47, and exerting its force to attain the object mentioned.

The pivoted arm 49, is provided upon its side towards the plunger rod 18, with a projection 52, which projects inwardly toward said plunger rod and is so located as to be in the path of a lug 53, on the collar 36, which lug on the downward movement of the plunger rod 18, strikes said projection 52, and throws 100 the arm 49 back out of engagement with the cross-head 40, permitting the stripper block to drop by gravity into place on the surface of the top blank on the pack *a*, there being sufficient space between the cross-head 40 105 and the collar 36, to permit the block 44 to gain on the head 19, and reach the stack in advance of the adhesive applying strips.

Means is provided for automatically supplying adhesive to the strips 21, at suitable 110 timed intervals in the operation of the machine when the head 19 is in elevated position. The means referred to is substantially the same as that shown in my application for Letters Patent heretofore mentioned, and 115 may be stated briefly as consisting of a tank or receptacle 54, for the liquid adhesive, a feed roller 55, to take the adhesive from the tank, a spreading roller 56, to distribute the same on the roller 55, and a supply roller 57 120 to which the adhesive is transferred by the roller 55. The roller 57 is journaled in a carriage 58 which travels back and forth beneath the strips 21, on a track 59 supported on the members 6, 6, of the arch 7, said roller 125 130

57 in its movements, contacting the strips 21, to distribute the adhesive thereon.

As heretofore stated, when the machine has stood motionless for a while and is then started up, a number of the blanks are liable to be imperfectly gummed or even destroyed, owing to the fact that the applying strips 21, have become dry or are only partially supplied with adhesive. To provide for the strips 21, being completely supplied with adhesive preparatory to the movement of said strips, into engagement with the blank, I provide means whereby the gumming head may be held in its elevated position against descent during the operation of the machine, which means is constructed as follows: Mounted upon the front of the arch 7, is a vertically extending arm 59, at the upper end of which is pivoted, as at 60, the lower end of a latch 61, formed with a lip 62, said latch being movable inwardly to permit the lip thereof to project under the block 28, to prevent downward movement of the plunger rod 18 and hold the head 19 in position to permit a distribution of the adhesive upon the strips 21. Projecting from the arm 59, is a bracket 63, having an opening 64, and extending through this opening is an operating handle 65, the inner end of which is pivoted to the upper end of the latch 61, as at 66. This handle 65 is provided on its under face with a recess 67, which, when the handle is pulled outwardly to withdraw the catch from under the block 28, co-operates with the wall of the opening 64, to lock the latch against inward movement.

In order to securely maintain the handle 65 with its recess in engagement with the wall of the opening, and also to serve as a means to automatically throw the catch into operative relation to the block 28, a contractile spring 68, is provided, having one of its ends connected to the handle 65 and the other secured to the bracket arm 59, at a point to one side the center of the pivot 60 of the catch, toward the plunger rod, the function of the spring being to exert a downward pull on the handle 65, and to throw the catch into the path of movement of the block 28. To lock the head against operation, when it reaches its uppermost position, the handle 65 is raised to free the recess from the bracket arm 63, and the spring exerts its force to throw the catch inwards until the lip 62 projects beneath the block 28, and engages the same for the purpose mentioned.

All of the elements being constructed and arranged as above described, the operation of the complete machine, is as follows: The elements being in the position shown in Fig. 1, and the disk 35 and cam 34 being rotated, the head 19 carrying the adhesive applying strips will start to descend and in its descent the lug 53 on the collar 36, will engage the projection 52 on the pivoted arm 49, to move

said arm outwardly against the force of the spring 51, and from engagement with the cross-head 40, which will release the cross-head and permit the stripper block 44, to descend by gravity, and said block then drops in advance of the strips 21, and reaching the blank before the said strips come into contact therewith, and serving to hold the same flat and stationary to permit the strips 21, to effectively apply the adhesive thereto. The blank having been gummed, the head 19 starts to move upwardly and continues such upward movement independently of the stripper block 44, which remains in place on the blank until the adhesive applying strips are completely free therefrom, at which time the continued upward movement of the plunger rod 18, brings the collar 36, into engagement with the cross-head 40, and the head 19 and stripper block then travel upward together, the block following the head, until the cross-head 40, is brought above the pivoted arm 49, which moves outwardly and engages said cross-head to hold the stripper-block in elevated position. The stripper block being locked against descent, the plunger-rod 18 descends a sufficient distance to bring the strips 21 below the under surface of the block 44, and the roll 57 may then operate to supply the adhesive to said strips after which the operation continues as above set forth.

It will be understood that subsequent to each impression made by the applying devices, and upon the up-stroke of the stripper, the blank just acted upon is removed by hand by the attendant in charge of the machine.

Having fully described my invention, what I claim and desire to secure by Letters Patent is:—

1. In a machine of the character described, the combination with a blank support, and an adhesive applying means having movement relative to each other, said means comprising a head provided with arms having adhesive applying strips adjustably mounted thereon and arranged to apply adhesive to opposite edges of a blank, of a reciprocating member, a stripper block detachably secured to said member, and arranged within the space bounded by said applying strips and having an area substantially co-extensive therewith, said block having a movement independent of the applying means whereby it is brought into engagement with the blank prior to the application of the adhesive to the blank, and means to remove the block from engagement with the blank after the adhesive has been applied to the latter.

2. In a machine of the character described, the combination with a blank support and an adhesive applying means having relative movement toward and away from each other, said means comprising a head provided with arms having adhesive applying strips adjust-

- ably mounted thereon and arranged to apply adhesive to opposite edges of a blank, a reciprocatory means moving across the path of movement of said head to supply adhesive to 5 the strips carried thereby, of a reciprocatory member, a stripper block detachably secured to said member, and arranged within the space bounded by said applying strips and having an area substantially coextensive 10 therewith, said block having a movement independent of the applying means whereby it is brought into engagement with a blank prior to the application of the adhesive to the blank, and means to remove the block from 15 engagement with the blank after the adhesive has been applied to the latter.
3. In a machine of the character described, a blank support, adhesive applying means movable toward and away from the support, 20 and means to hold the blank during the application of adhesive, said means being actuated by the applying means.
4. In a machine of the character described, a blank support, adhesive applying devices 25 movable toward and away from the support, a blank holding means, supporting means to maintain said holding means removed from the blank, and means whereby the applying devices control the supporting means.
5. In a machine of the character described, a blank support, reciprocating adhesive applying mechanism moving toward and away from the support, blank holding means also 30 movable toward and away from the support, locking means to maintain said holding means normally removed from the support, and means carried by the applying mechanism and coöperating with the locking means to release the holding means on the down- 35 ward stroke of the applying mechanism.
6. In a machine of the character described, a blank support, a plunger carrying adhesive applying devices, and movable toward and away from the support, reciprocating rods 40 carrying holding means to hold the blank during the application of adhesive, a cross-head on said rods, a catch engaging the cross-head to maintain the holding means elevated, the plunger coöperating with the catch to 45 move the same away from the cross-head to release the holding means.
7. In a machine of the character described, a blank support, a plunger carrying adhesive applying devices, and movable toward and away from the support, reciprocating rods 50 carrying holding means to hold the blank during the application of adhesive, a cross-head on said rods, a catch engaging the cross-head to maintain the holding means elevated, 55 the plunger coöperating with the catch to move the same away from the cross-head to release the holding means on the down stroke of the applying means.
8. In a machine of the character described, 60 a blank support, a plunger carrying adhesive applying devices, and movable toward and away from the support, reciprocating rods carrying holding means to hold the blank during the application of adhesive, a cross-head on said rods, a catch engaging the cross-head to maintain the holding means elevated, 65 the plunger coöperating with the catch on its down stroke to release the holding means to engage a blank, and on its up-stroke engaging the cross-head to lift the holding means.
9. In a machine of the character described, a blank support, adhesive applying devices for applying adhesive to the marginal edges of a blank, means for causing a relative 70 movement between the support and applying devices, whereby to bring said devices into engagement with the blank, a stripper for retaining the blank on the support after the gum applying devices have acted, the 75 stripper being controlled in its operation by the relative movement of the adhesive supplying devices and the blank support.
10. In a machine of the character described, a blank support, adhesive applying devices, means for applying adhesive to said devices, means to hold said devices stationary in position to receive adhesive while permitting the continued operation of the machine, and mechanical means for maintaining 80 said holding means in its active and in its inactive positions.
11. In a machine of the character described, a blank support, adhesive applying devices, a block carried by said devices, adhesive supplying means, a catch coöperating with the block to hold said devices stationary in position to receive adhesive while permitting the continued operation of the machine, and mechanical means for holding said 85 catch in its active and in its inactive positions.
12. In a machine of the character described, the combination of a blank support, adhesive applying devices, means for reciprocating said devices to and from the support, means for supplying adhesive to said devices, a blank engaging element, and means for causing the active portions of said glue applying device to move below the plane of 90 said blank engaging element to receive a supply of glue, the blank engaging element to then move into contact with a blank in advance of the glue applying device, and maintain such contact until the glue applying device has receded.
- In testimony whereof I have hereunto set my hand in presence of two subscribing witnesses.
